UNITED STATES PATENT OFFICE.

THOMAS SIMMONS HOMANS, OF BROOKLYN, NEW YORK, ASSIGNOR TO MERGENTHALER LINOTYPE COMPANY, A CORPORATION OF NEW YORK.

LINOTYPE-MACHINE.

No. 825,054.

Specification of Letters Patent.

Patented July 3, 1906.

Application filed March 26, 1906. Serial No. 308,043.

To all whom it may concern:

Be it known that I, THOMAS SIMMONS HOMANS, of the borough of Brooklyn, county of Kings, and State of New York, have invented 5 a new and useful Improvement in Linotype-Machines, of which the following is a specification.

My invention relates to that class of linotype-machines in which circulating matrices, each containing two separately-usable characters, are combined with assembling mechanism whereby each matrix entering the composed line may be set to a higher or a lower lever in order to bring one or the 15 other of its characters into line for use, as shown, for example, in United States Patents No. 547,633 to P. T. Dodge and No. 615,909 to J. R. Rogers. In these machines the matrices are delivered one after another 20 into a channeled support known as the "assembler-elevator," which is movable vertically in order to raise the completed line preparatory to its being transferred horizontally from the elevator through a stationary 25 channel, known as the "intermediate" channel, toward the devices for presenting the matrices to the mold.

In the Rogers patent the assembling-elevator is provided with a horizontal blade located at the receiving end and movable forward and backward transversely to the line, so that it may be withdrawn from the path of the matrices in order to permit them to descend to the normal level with their upper 35 characters in line or moved backward into the path of the incoming matrices in order to sustain them at the higher level until they are advanced laterally to a second sustaining-blade.

40 My invention relates to a substitute for the two blades of the Rogers patent; and to this end it consists in a single continuous blade mounted in the elevator and movable in the direction of the length of the line, so that it 45 may be moved backward from the path of the incoming matrices to permit their downward passage or advanced into the path of the matrices in order to arrest and sustain them. This movement of the blade length- 50 wise of the line instead of transversely, as heretofore, is advantageous in that the gap or opening for the downward passage of the matrices may be varied at will, so that, if desired, all but the last matrix in the line

may be maintained in the upper position, an 55 action not possible with the Rogers structure. When the slide is moved back to permit the descent of the incoming matrices, its opposite end is projected beyond the delivery side of the assembling-elevator, so that when 60 the elevator is raised to a higher level and the matrix-line moved horizontally out of the elevator into the intermediate channel the projecting end of the blade overlying the ears of the lower matrices will hold them down in 65 position and prevent them from catching or binding during their transfer across the joint or gap between the elevator and the channel.

Referring to the accompanying drawings, Figure 1 is a front elevation of the assembling-elevator and attendant parts with the blade in position to permit matrices to pass to the lower level. Fig. 2 is a horizontal section of the same on the line 2-2. Fig. 3 is a similar section with the blade moved to the 75 right to sustain all the matrices at the higher level. Fig. 4 is a perspective view looking forward against the front wall or side of the assembling-elevator with a line of matrices therein and the blade in position to sustain 80 them at the higher level. Fig. 5 is a similar view with the blade retracted to permit the passage of matrices to the lower level.

Referring to the drawings, H represents the inclined carrier-belt, on which the matrices Y, released from the magazine, pass down successively into the channel and the top of the assembling-elevator I, into which they are urged laterally by the star-wheel h². Each matrix is provided with two independent characters or matrices proper, y and y³. The assembling-elevator is mounted to move vertically in order to lift the composed line to the transferring-level. All of the foregoing parts are constructed and operated in a 85 manner already known in the art. In applying my improvement I provide the assembling-elevator I with a horizontal slot or groove i to extend practically its entire 90 length, and in this slot I mount a single longitudinally-movable blade J, projecting inward beyond the inner wall of the elevator in position to overlie the lower ears of the matrices when the latter stand at the lower or normal level in the elevator. The blade has 95 its inner or operative edge continuous and of the length of the longest line to be assembled. The blade is provided with longitudi- 100 105

nal slots j , which receive guiding-pins j' in the elevator, this arrangement permitting the blade to be moved endwise the distance of half an inch more or less. When moved 5 to the extreme right, its end stands near the star-wheel h^2 and in such position that all the incoming matrices will encounter the blade and be sustained thereby with their lower characters at the alining-level as they are advanced 10 along the elevator toward the left. When, however, the blade is retracted endwise to the left, as shown in Figs. 1, 2, and 5, a gap is left between its right end and the star-wheel, so that the incoming matrices 15 may pass the end of the blade and descend to the lower level in the elevator, their upper characters being thus brought to the alining-level and their ears passing beneath the blade. It will be seen that by simply shifting the 20 blade endwise the matrices may be caused to assemble at the upper or lower level. By advancing the blade to the right, so that the gap will permit the descent of a single matrix only, it is possible to compose a line in which all the matrices except one or two at the 25 extreme right will be sustained at the upper level. When the blade is moved to the left, as shown in Figs. 1, 2, and 5, its left end projects beyond the elevator I, as shown. When 30 the elevator is thrown upward from the composing position to the position for delivering the matrix-line endwise into the channel K, the projecting end of the blade overlying the ears of the matrices will prevent them from jumping upward above the proper level, as there is a tendency to do when the elevator 35 is thrown rapidly upwardly and suddenly arrested.

The blade is provided with a handle j^2 , by 40 which it may be readily moved to and fro. It may be provided with any other suitable operating device. The slots and pins may be replaced by any other suitable means for guiding the blade.

I believe myself to be the first to combine 45 with the assembling devices a continuous blade movable longitudinally in such manner as to control the level of the incoming matrices, and this I claim, broadly, in any form and arrangement the mechanical equivalent 50 of that herein shown.

Having described my invention, what I claim is—

1. In a linotype-machine, the assembling-elevator provided with a longitudinally-movable 55 blade to control the height of the incoming matrices.

2. In a linotype-machine, the combination of a channeled assembler, means for delivering matrices successively thereto, and a 60 blade mounted in the assembler and movable endwise to and from the path of the incoming matrices.

3. In a linotype-machine provided with two-letter matrices, the assembler, the star-wheel 65 to deliver matrices thereto, and the horizontal longitudinally-movable blade extending the entire width of the assembler.

4. In combination with the vertically-movable assembling-elevator and the intermediate channel to receive the matrix-line 70 therefrom, an blade mounted in the elevator and movable endwise to extend beyond the same, whereby it is adapted to hold the matrices down within the elevator in position to 75 be transferred therefrom.

5. In a linotype-machine, a blade forming a member of the assembling mechanism and arranged to receive and sustain a line of matrices, said blade arranged for retraction end- 80 wise at will to a greater or less extent.

In testimony whereof I hereunto set my hand, this 24th day of March, 1906, in the presence of two attesting witnesses.

THOMAS SIMMONS HOMANS.
